IGNITION INDUCTION COUPLER FOR INTERNAL COMBUSTION ENGINE OR THE LIKE

Delbert N. Wall, Box 848, Burlington, Colo. 80807

Filed Feb. 21, 1974, Ser. No. 444,471

Term of patent 14 years

Int. Cl. D13—03

U.S. Cl. D26—1 R

FIG. 1

FIG. 2

FIG. 3

FIG. 4

FIG. 5

FIG. 1 is a perspective view of an ignition induction coupler for internal combustion engine or the like showing my new design;

FIG. 2 is a top plan view thereof;

FIG. 3 is a bottom plan view thereof;

FIG. 4 is a side view thereof; and

FIG. 5 is an end view of the ignition induction coupler. I claim:

The ornamental design for an ignition induction coupler for internal combustion engine or the like, substantially as shown.
